TRIPOD JACK

Ralph G. Shroyer, Columbus, Ohio, assignor of one-third to Harry L. Mellman and one-third to Myer W. Mellman, Columbus, Ohio

Application November 20, 1953, Serial No. 393,310

5 Claims. (Cl. 254—99)

This invention relates to jacks, and more particularly to improvements in jacks of the tripod type for use in service stations, garages, farms, industry, et cetera.

The object of this invention is to provide a jack of the tripod type wherein the legs and the main frame members can be made of sheet metal, and at the same time be of strong and sturdy structure, effectively reinforced.

A further object of the invention lies in the provision of positively effective means for camming the legs of the tripod outwardly when in operating position and in camming them inwardly into close parallelism for storing and transporting.

A further object of the invention is simplification of structure achieved by the provision of means integral with the sheet metal load bearing main frame for the support of the load.

A further object of the invention is the provision of a handle so formed that its path of travel is stopped at a point before it reaches a vertical position, so that it is prevented from complete rotation and cannot travel over the top of the tripod.

A further object of the invention is the provision of means on the handle for holding the handle in a fixed operative position when load is applied, the strength of the means being proportional to the amount of the load applied.

Other objects and advantages reside in the construction of parts, the combination thereof and the mode of operation, as will become more apparent from the following description.

In the drawings, Figure 1 is a perspective view showing the device in operative position.

Figure 2 is a cross sectional view taken on the line 2—2 of Figure 1.

Figure 3 is a rear elevational view of the top portion of the device, and showing the bearing in cross section.

Figure 4 is a fragmentary cross sectional view taken on the line 4—4 of Figure 3, with leg members incomplete.

Figure 5 is a detail view as seen from the direction of the arrows 5—5 in Figure 3.

Figure 6 is a fragmentary top plan view, showing portions of leg members incomplete.

Figure 7 is an elevational fragmentary view of the load bearing member with portions of the main frame member broken away.

The main frame or channel member 10 is of channel formation and the forward edges of its side walls 12 are each provided with flanges 13. The side walls 12 of the channel member 10 are provided adjacent their upper ends with offset stamped out portions or cam surfaces 14. The formation of these cam surfaces is best seen in Figure 4. Toward the forward edge of the channel side wall, the offset portion, as shown at 11 in Figure 4, is extremely shallow, deepening as it progresses toward the rear wall of the channel member 10, as shown at 14.

The side walls of the main frame member 10 are provided with reinforcing ribs 18, stamped or otherwise

2

formed into the sheet material of the frame. The rear wall of the channel member 10 is extended into a flap at its upper end, and is bent forwardly to a substantially right angular position with respect to the side and rear walls of the channel member 10, and forms a seat 20 for a bearing assembly that will be more fully described.

Openings 22 in the side walls of the main frame member 10 receive lugs 21 of a plate 24. A foot member 26 is welded or otherwise secured to the lower end of the main frame or channel member 10. The foot member 26 may be provided as desired with ribs 28, or any other suitable reinforcing means.

A pair of sheet metal or other angle irons 30 provide the second and third legs of the tripod. These angle irons 30 are pivotally attached by means of rivets 16 to the outer surfaces of the side walls of the channel member 10 at the positions of the slanting offset cam portions 14. The angle irons 30 are provided with portions 31 substantially horizontally disposed when the legs are spread, and welded or otherwise secured to a pair of feet members 33.

Seated upon the upper surface of the seat member 20, and supported by it is a bearing assembly 32 comprised of a lower ball race 34, an upper ball race 36, and ball bearings 38.

Seated upon the upper surface of the ball race 36 is a washer 40.

The members 20, 34, 36 and 40 are each provided with circular openings which are adapted to receive the upper end 41 of a lifting screw 44. The said upper end 42 of the lifting screw 44 is provided with a diametrically disposed opening 41 which is adapted to receive a horizontally disposed portion 48 of a handle 50.

The lower end of the lifting screw 44 is provided with a reduced cylindrical portion 45 forming a shoulder 47. The plate 24 also is provided with a circular opening which receives the reduced portion 45, and functions as a seat for the shoulder 47.

The upper end 42 of the lifting screw 44 is provided with a plurality of stops 46 which are punched out of the surface of the upper end member 42, and are integral therewith. These stops limit the upward movement of the lifting screw.

The lifting screw 44 is prevented from downward movement by the horizontally disposed portion 48 of the operating handle 50, which is received in the opening 41.

The portion 48 of the handle 50 rests upon the washer 40 and is provided with a flattened portion 52. The operating handle 50 includes a hand hold 54, a portion 56 of sufficient length to provide leverage, a previously indicated portion 48 disposed at a substantial right angle to the portion 56, and a curved portion 58 disposed between, and connecting portions 48 and 56. This formation can be more readily understood when the members 48 and 58 are considered as the vertical portion and the curved portion respectively of a question mark.

A load lifting member 60 is formed of an integral portion of heavy sheet material formed into a sleeve 66 adapted to receive the lifting screw 44 in a loose sliding relationship, and a pair of flaps meeting at 68 and riveted or otherwise secured together, as shown at 70, 72 and 74.

The outwardly extending portions 76 of the flaps 68, together with notches 64 therein, provide means for engaging and carrying the load to be lifted, as for example, the bumper of a car.

An internally threaded sleeve 78 engages threads 43 of the lifting screw 44. The outer surface of the sleeve 78 is of rectangular formation and is prevented from rotation by its close fit within the complementary formation of the side and rear walls of the channel member 10. The sleeve 78, therefore, travels upwardly or down-

wardly along the lifting screw as the screw rotates, its direction depending upon the direction of rotation applied to the handle 54. The sleeve 66 rests upon and is lifted and lowered with the upwardly and downward movement of the sleeve 78. Thus, the load carrying member 76 receives its upward and downward impetus.

The various functions of most of the various parts have now become evident.

It will be seen that the cam surfaces 14 guide the legs 30 outwardly away from each other as they swing outwardly away from the main frame member 10. As they swing inwardly and approach the main frame member, they assume a relation of parallelism. In operative position, the members 30 and 10 become a tripod with legs extended and held positively in extended position. In a position of non-use, or for storing or carrying, the members 30 and 10 lie parallel and closely together.

The function of the peculiar formation of the right angularly disposed portions 48 and 56 of the handle 50, together with the intervening curved portion 58 and the flattened portion 52, is as follows:

When load is applied at 60, the downward pressure causes the handle to come to rest and remain with the flattened portion 52 downwardly and pressing upon the disc 40. The greater the load, the more firmly this position is maintained.

When the handle 50 is lifted, the curved portion 58 of the handle abuts the disc 40 and the handle is stopped from continued travel over the top of the tripod.

A tripod jack is thus produced that is easily used, efficient and at the same time low in cost of production.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A duo-functional operating handle of round single piece bar stock for use in a tripod jack having a sheet metal main frame member of channel formation comprising a rear wall and a pair of side walls, an apertured flap member integral with the rear wall and overlying the upper end of the channel member, a bearing assembly seated upon said flap, a lifting screw rotatably mounted within said channel member, a portion of said lifting screw adjacent its upper end extending through openings in said bearing assembly, said lifting screw being provided with a transverse hole above the flap member, said operating handle being characterized by a horizontal portion on said handle extending through the transverse hole in the lifting screw at the upper end thereof to thereby support the screw on the bearing assembly, a portion of the surface of the horizontal portion of the handle being flattened to engage the upper surface of the bearing assembly whereby load applied to said load lifting means is transmitted through the horizontal portion of the handle to the bearing assembly and thence to said flap, said flattened portion holding the handle in a horizontal position when load is applied to the lifting screw.

2. In a jack of the tripod type, a sheet metal main frame member adapted to receive a lifting screw, and comprising a rear wall and a pair of side walls, each of said side walls being provided adjacent its upper end with an offset bulging cam portion, said bulging cam portion being inclined outwardly from the forward edge of the side wall, a pair of legs, one of said legs being pivotally mounted on one side of the offset bulging cam portion, and the other leg being pivotally mounted on the other

bulging cam, said legs being cammed outwardly to extended position, and cammed inwardly towards the sheet metal main frame member to a position of close parallelism when not in use.

5. 3. In a jack of the tripod type, a sheet metal frame member receiving a lifting screw, said main frame member being of channel formation and comprising a rear wall and a pair of side walls, ribs on selected ones of said walls for reinforcement, said ribs terminating in spaced relation from one end of the walls, stamped out cam portions integral with and forming an integral part of the surface of said side walls at points adjacent their upper surfaces, said cam portions being inclined outwardly from the forward edge of the side walls, a leg pivotally mounted on the outer surface of each cam portion, each of said legs being cammed outwardly into positions of use, and inwardly into close parallelism to a position of non-use.

4. A jack of the tripod type comprising a sheet metal main frame member of channel formation including a rear wall and a pair of side walls, a lifting screw mounted in said main frame member, a bulging cam portion stamped into and forming an integral part of each of the surfaces of said side walls at positions adjacent their upper ends, said cam portions being inclined outwardly from the forward edge of the side walls, a leg pivotally mounted upon the outer surface of each of said side walls and being cammed outwardly as they are rearwardly swung to positions of use, and are cammed inwardly to positions of close parallelism when not in use, a flap portion forming an integral extension of one of the walls of said main frame at its upper end, bent at a substantial right angle thereto, a bearing assembly seated upon said flap, a single piece handle of round bar stock having a horizontally disposed flattened portion secured to the upper end of the lifting screw, said flattened portion holding the handle in a horizontal position by the load upon the lifting screw, said flattened portion being then supported by the upper surface of the bearing assembly, 40 said handle also provided with a portion of sufficient length to provide leverage for rotation, and a curved portion disposed between said horizontal portion and said leverage providing portions of said handle, said curved portion providing a stop for preventing the handle 45 from complete rotation over the top of said jack.

5. A duo-functional handle of round bar stock for use in a jack of the tripod type having a screw provided with a load supporting member, said handle comprising a horizontal portion supporting the screw extending above 50 the frame of the jack, a portion for providing leverage for rotation disposed at a substantial right angle to the said horizontal portion, a curved portion disposed and forming connection between the said horizontal portion and said leverage providing portion, said horizontal portion 55 of said handle resting on top of the frame of the jack and supporting the load upon the supporting member, said horizontal portion being provided with a flattened portion for aiding in seating the handle and holding the handle in horizontal position when a load is supported by the 60 jack, said curved portion providing a stop for preventing rotation of the handle over the top of said jack.
